(57) **CLAIM**

The ornamental design for medical multi way stopcock handle, as shown and described.

DESCRIPTION

2. Medical multi way stopcock handle

2.1 : Perspective

2.2 : Front

2.3 : Back

2.4 : Left

2.5 : Right

2.6 : Top

2.7 : Bottom

The subject design provides a medical multi way stopcock handle in a form of an empty passage in the middle so that the flow of fluid or the like can be identified more intuitively than using a conventional handle.
